UNITED STATES PATENT OFFICE.

WILLIAM H. AMOS, OF AKRON, OHIO, ASSIGNOR OF ONE-HALF TO LEROY R. FRANK, OF SAME PLACE.

RUBBER SHOE.

SPECIFICATION forming part of Letters Patent No. 351,305, dated October 19, 1886.

Application filed April 16, 1886. Serial No. 199,104. (No model.)

To all whom it may concern:

Be it known that I, WILLIAM H. AMOS, a citizen of the United States, residing at Akron, in the county of Summit and State of Ohio, have invented a new and useful Improvement 5 in Retaining Devices for Rubber Overshoes, of which the following is a specification.

My invention has relation to improvements in devices for retaining rubber overshoes upon the shoe and preventing the heel from slipping down. Heretofore this has been sought to be accomplished by lining the entire interior of the heel of the overshoe with a layer of vulcanized rubber. This construction is 15 objectionable, because the frictional rubber lining becomes filled with dust, dirt, and blacking, thereby losing its retentive property, and also not only removes the gloss, finish, and blacking from the shoe, but also wears the 20 leather.

The objects of my invention are to accomplish the result attempted by the construction referred to, and to avoid the objections to such construction.

25 My invention consists in the device illustrated in the accompanying drawing, as hereinafter described and claimed.

The accompanying drawing represents, in

perspective, a portion of a rubber overshoe embodying my invention.

Upon the inner upper surface of the heel of the overshoe A is a narrow band or strip of rubber, B, all other parts of the interior being lined with the soft fabric in common use. The strip B may have a plain or roughened face, 35 and its length and breadth will depend upon the style, size, and class of overshoe. This strip bears upon the softer part of the shoe above the counter, and, while it yields to the movements of the shoe, retains the heel of the 40 overshoe from slipping down, and does not wear the shoe above the counter, nor become filled with dirt and blacking.

I claim—

In combination with a rubber overshoe, a 45 corrugated strip of rubber attached at the inner upper face of the heel, substantially as shown, and for the purpose specified.

In testimony that I claim the foregoing I have hereunto set my hand this 31st day of 50 March, A. D. 1886.

WILLIAM H. AMOS.
